UNITED STATES PATENT OFFICE.

HARRY J. PURPLE, OF NEWTON, MASSACHUSETTS, ASSIGNOR TO UNITED DRUG COMPANY, OF BOSTON, MASSACHUSETTS, A CORPORATION OF MASSACHUSETTS.

SHAVING-STICK.

1,320,351.

Specification of Letters Patent.

Patented Oct. 28, 1919.

Application filed June 23, 1919. Serial No. 306,240.

To all whom it may concern:

Be it known that I, HARRY J. PURPLE, a citizen of the United States, and a resident of Newton, county of Middlesex, and State 5 of Massachusetts, have invented an Improvement in Shaving-Sticks, of which the following description, in connection with the accompanying drawings, is a specification, like characters on the drawings representing like parts.

This invention relates to shaving sticks and like articles which are used in a similar manner, by rubbing them, and more particularly to that type of shaving stick wherein 15 the container also serves as a holder by which the stick proper or soap bar may be handled. As shaving sticks are the most generally known articles to which my invention is applicable, I shall herein refer particularly to a shaving stick, using that expression in an exemplary sense.

My invention will best be understood by the following description of the illustrative embodiment thereof shown in the accompanying drawings wherein:

Figure 1 is a side elevation of the complete package;

Fig. 2 is a similar view showing the cover removed;

Fig. 3 is a side elevation, partly broken away, showing how the last portion of the soap bar may be used; and

Fig. 4 is a plan view of the soap bar removed.

In accordance with my invention I provide a soap bar 5 which may be of cylindrical form, that is, of uniform section throughout its length. Usually it will be cylindrical in the narrower sense of that 35 word, meaning a right circular cylinder. The stick is here shown as inclosed in a case or package of metal which may embody the bottom or handle portion 7 and the cover portion 9, which conveniently are of counterpart form for reasons hereinafter stated.

To support the soap bar 5 in the handle portion 7, the former is provided with a ring 11 conveniently in the form of a bendable band which may be wound around the stick 50 between its ends, as shown in Fig. 4, forming a broken ring encircling the same. This ring may be provided with suitable means for interlocking with the stick and I have herein shown struck-up prongs 13. The

ring 11 is conveniently positioned centrally, 55 as indicated in Fig. 2.

The main portion of the hollow handle 7 may be of substantially the same size as the stick 5 and the outer end may be belled to provide the annular seat 15 (Fig. 3) receiving the ring 11, from which seat rises the cylindrical flange 17 embracing the broken ring and holding it in its encircling gripping relation about the soap bar 5. Suitable co-operating catch means 19 may be provided 65 on the flange and the ring. The cover portion 9 may be of substantially similar construction, the bell portion providing a like cup-like enlargement receiving the outer end of the ring or band 11, the two portions 7 70 and 9 forming a complete inclosing casing for the soap bar.

When the shaving stick is first used, it will have, when the cover 9 is removed, the appearance shown in Fig. 2 and the upper end 75 portion of the bar 5 may be used until worn away. It will be noted that the handle portion 7 is of considerable length which permits the hand firmly to grasp the same, the bottom resting against the palm while the 80 fingers hold the metal of the container instead of the possibly wet soap itself. After the upwardly projecting half of the bar is worn away, it may be reversed bodily, the opposite end of the band 11 then resting on 85 the seat 15 of the part 7. If desired, however, the stick may be removed and the band 11 unbent and clamped around the stick lower down. This may be done as a final 90 economy permitting the utilization of the stick practically to the end, as indicated in Fig. 3 wherein it may be supposed that the stick has been used in its initial and in its reversed position until two small stumps were left on either side of the band 11. The 95 band was then unbent and clamped about the remaining small portion of the stick flush with one end thereof, thus providing a projecting end of considerable extent, as indicated in the figure, ready for use.

It is of some importance that the form of my invention here shown permits the use of a stick of uniform cross section and not specially formed in any way, as this is a desirable initial simplification and permits 105 as well the shifting of the stick in the holding ring, as described.

The various parts may be very simply

manufactured, without any comparatively expensive operation such as metal spinning, and the assembly of the band 11 on the stick presents no difficulties. In fact, this may 5 be done by an entirely unskilled person and the user may buy additional soap bars and use them with his old holder by simply unbending the flexible band 11 and wrapping it about the bar in the manner indicated in Fig. 4. The belled end of the holder will hold the bar in place and provides a firm support for the same preventing undue wobbling of the stick in use.

I am aware that it has been proposed to 15 provide a shaving stick with counterpart box portions one of which would serve as a handle in which the stick could be reversibly mounted, and I therefore do not claim that idea broadly. The principles which are exemplified by the form of my invention here 20 illustrated and which I claim as new and desire to secure by Letters Patent, I shall express in the following claims.

I claim—

25 1. A shaving stick comprising a cylindrical soap bar, an encircling band about the same between the ends thereof, and complementary container parts having enlarged open ends providing cup-shaped seats for 30 the band.

2. A shaving stick comprising a cylindri-

cal soap bar, a bendable band encircling the same and having portions to interlock the bar and a hollow handle portion having an open end flanged to provide a cup-like enlargement receiving said band. 35

3. A shaving stick comprising a cylindrical soap bar, a band wound about the same having projections interlocking with the bar and a handle portion having an annular 40 seat receiving the band provided with a flange embracing the same.

4. A shaving stick comprising a soap bar having a ring around the same between its ends and a hollow handle portion having an 45 open end belled to provide a seat closely receiving said ring.

5. A shaving stick comprising a soap bar, a broken ring having projections entering the bar and a hollow handle portion having 50 an annular seat receiving the ring provided with a flange surrounding the same and holding it in gripping relation to the bar.

6. A shaving stick comprising a cylindrical soap bar, a band wound about the same 55 having projections interlocking with the bar and a handle portion having an open end receiving the band and having means interlocking therewith to support the same.

In testimony whereof, I have signed my 60 name to this specification.

HARRY J. PURPLE.
